by
Robert A. Young

UNITED STATES PATENT OFFICE

CHARLES HUGH DUFFY, OF MIAMI, FLORIDA

DIAPHRAGM FOR RADIO LOUD SPEAKERS

Application filed March 31, 1931. Serial No. 526,663.

(GRANTED UNDER THE ACT OF MARCH 3, 1883, AS AMENDED APRIL 30, 1928; 370 O. G. 757)

The invention described herein may be manufactured and used by or for the Government for governmental purposes, without the payment to me of any royalty thereon.

5 The invention relates to diaphragms for radio loud speakers and the like, and has for its object to provide improvements in such diaphragms as disclosed in my co-pending application for radio loud speakers, Serial

10 Number 447,390, filed April 25, 1930.

In a diaphragm which is flexed into two substantially partially circular formations, and preferably into two substantially quarter-circle formations, I have found that when 15 the diaphragm is pulsated by a drive unit or units applied to the central meeting-edge-portions of the flexed diaphragm, there exists a tendency for the diaphragm to "whip" along the central meeting-edge-portions, so 20 that the end portions of the diaphragm do not pulsate uniformly with the intermediate portions thereof, but under the influence of imparted pulsations of large amplitude, the said end portions pulsate out of step with 25 the central portion of the diaphragm.

For the highest efficiency, it is desirable that the entire central meeting edge portions of the diaphragm move bodily and uniformly in response to the pulsations impressed upon it. If there be any "whipping" of the end portions out of step with the central portion of the diaphragm, such "whipping" is taken up by the entire diaphragm and it is set in a state of false vibration or chattering, 35 which is highly detrimental to the purity and fidelity of the reproduced sound.

This present invention seeks to correct this tendency in diaphragms of this class, and thereby enhance their efficiency.

40 Referring to the accompanying drawings.—

Fig. 1 is a diagrammatic side elevation of a diaphragm constructed in accordance with this invention.

45 Fig. 2 is a top plan view of the same.

Fig. 3 is a horizontal sectional view of such a diaphragm made of celluloid or material of like characteristics.

Fig. 4 is a similar view of a modification of a diaphragm of such material, and

50 Fig. 5 is a similar view of a further modification.

Like numerals of reference indicate the same parts throughout the several figures, in which

55 1 indicates the diaphragm, which when constructed as shown in Figs. 1 and 2 may be of any suitable diaphragm material. The diaphragm 1 when so constructed may be made of two sheets of material 2, joined together at 3. It will be seen that I prefer to have the line of juncture 3 of the sheets curved rearwardly from the ends to the center so that the two ends 4 of the diaphragm are reduced in area to less than the area of the intermediate portion. When the diaphragm is flexed the transverse curvature of the flexed sheets progressively change from the center of the diaphragm toward both ends thereof as indicated in Fig. 2. The effect of this is that when the side edge portions 5 are clamped to hold the diaphragm in operative flexed position, the end portions are slightly stiffened, and of course, the diaphragm is gradually reduced in area and 60 mass toward the end portions.

65 Referring to Fig. 1, it will be seen that the material forming the diaphragm extends materially in rear of the line of juncture 3 of the flexed sheets to form a positive stiffening area 6, and as shown in Fig. 2, a layer 70 of sound damping material may be interposed between the sheets of diaphragm material throughout the whole of this stiffening area, or this layer 7 may be of suitable 75 stiff material different from that of the diaphragm material as proposed for Fig. 5. Throughout this stiffening area 6, the diaphragm material is preferably flat and without transverse curvature, so as to present an 80

area of material lying edgewise in the direction of the plane of the impressed pulsations, the extent of which stiffening area is sufficient to prevent the end-portions 4 of the 5 diaphragm from "whipping" out of step with the intermediate portion of the diaphragm upon which the pulsations are impressed and to insure that the entire central meeting edge portion 8 of the diaphragm moves bodily in 10 response to the pulsations impressed upon the stiffening area 6 by the actuating unit or units.

Referring to Fig. 3, it is seen that I may construct the diaphragm out of a material 15 such as celluloid, wherein the material is of such a character that a single sheet of sufficient thickness may be partially split as by a saw or other suitable implement to form the two flexed diaphragm portions 2 and leave 20 unsplit the stiffening area 6. In such construction the diaphragm portions 2 are integral and there is no need for the sound damping material at the stiffening area, because the flexed portions 2 of the diaphragm 25 will be sufficiently and effectually spaced apart by the unsplit stiffening area 6 so that these flexed portions 2 will not strike against each other when in a state of vibration.

Referring to Fig. 4, it will be seen that 30 such a diaphragm of celluloid or of material of like characteristics may be made to form an integral structure by inserting a piece 6¹ of the same material as that of the diaphragm proper between the lapping surfaces which 35 form the stiffening area 6. A material such as celluloid may, by the application of a suitable solvent to the surface thereof, be caused to unite with the surface of a piece of like material to form an integral or unitary structure. When, therefore, the 40 surfaces of the spacing piece 6¹ and those of the immediately adjacent diaphragm portions 2 are treated by a suitable solvent or otherwise made plastic by any known manner, and 45 such surfaces united by pressure, a unitary structure will be the result, which will be substantially the same as when the diaphragm is split from a single thick sheet of material as illustrated in Fig. 3.

Referring to Fig. 5, it will be seen that the 50 stiffening area 6 may be made of a piece 7¹ of suitable stiff material which spaces the diaphragm formations apart and which may or may not be of the same material as that 55 of the diaphragm portions 2. With such construction, I may interpose a thin layer 8¹ of sound damping material such as felt between the contiguous surfaces of the piece 7¹ and of the diaphragm portions 2, so that concurrent vibration of the contiguous surfaces will 60 not result in the surfaces striking each other when in a state of vibration.

The invention is susceptible of further 65 modifications, those herein described being by way of example. In each instance, how-

ever, it is preferable to construct the diaphragm with a stiffening area of sufficient capacity to insure against whipping of the ends of the diaphragm so that it cannot pulsate out of step with the intermediate portion, and so that it will insure the whole central meeting edge portion of the diaphragm moving bodily in response to the pulsations impressed upon the stiffening area 6 by the actuating unit or units.

While the word "celluloid" is recited in several of the claims, it is intended that such word define also such materials as may have characteristics like the well known characteristics of celluloid, but which may be known under or designated by other trade-names.

What I claim as new and desire to secure by Letters Patent of the United States is:

1. A diaphragm for radio loud speakers or the like of substantially partially circular formations having a central meeting portion, edge portions and end portions, the line of juncture at the central meeting portion being curved rearwardly from the ends to the center, and a positive stiffening area in rear of the line of juncture of the flexed portions, said stiffening area being of a capacity sufficient to prevent whipping of the end portions and insure bodily movement of the entire central meeting portion of the two flexed portions of the diaphragm.

2. A diaphragm for radio loud speakers or the like of suitable material flexed into substantially quarter-circle formations, having a central meeting portion, edge portions and end portions, the line of juncture at the central meeting portion being curved rearwardly from the ends to the center, and a positive stiffening area in rear of the line of juncture of the flexed portions, said stiffening area being of a capacity sufficient to prevent whipping of the end portions and insure bodily movement of the entire central meeting portion of the two flexed portions of the diaphragm.

3. A diaphragm for radio loud speakers or the like of suitable material flexed into two substantially partially circular formations having a central meeting portion, edge portions and end portions, a positive stiffening area in rear of the line of juncture of the flexed portions, said stiffening area being of a capacity sufficient to prevent whipping of the end portions and insure bodily movement of the entire central meeting portion of the two flexed portions of the diaphragm.

4. A diaphragm for radio loud speakers or the like of suitable material flexed into two substantially quarter-circle formations having a central meeting portion, edge portions and end portions, a positive stiffening area in rear of the line of juncture of the flexed portions, said stiffening area being of a capacity sufficient to prevent whipping of the end portions and insure bodily movement of the entire central meeting portion of the two flexed portions of the diaphragm.

end portions and insure bodily movement of the entire central meeting portion of the two flexed portions of the diaphragm.

5. A diaphragm for radio loud speakers or
5 the like of celluloid flexed into two substan-
tially partially circular formations having a
central meeting portion, edge portions and
end portions, the line of juncture at the cen-
tral meeting portion being curved rearward-
ly from the ends to the center, and a positive
stiffening area in rear of the line of juncture
of the flexed portions, said stiffening area
being of a capacity sufficient to prevent whip-
ping of the end portions and insure bodily
10 movement of the entire central meeting por-
tion of the two flexed portions of the dia-
phragm.

15

1. A diaphragm for radio loud speakers or the like of celluloid flexed into two substantially quarter-circle formations having a central meeting portion, edge portions and end portions, the line of juncture of the central meeting portion being curved rearwardly from the ends to the center, and a positive stiffening area in rear of the line of juncture of the flexed portions, said stiffening area being of a capacity sufficient to prevent whipping of the end portions and insure bodily movement of the entire central meeting portion of the two flexed portions of the diaphragm.

35 7. A diaphragm for radio loud speakers or the like of celluloid flexed into two substantially partially circular formations having a central meeting portion, edge portions and end portions, a positive stiffening area in rear of the line of juncture at the central meeting portion of the flexed portions, said stiffening area being of a capacity sufficient
40 to prevent whipping of the end portions and insure bodily movement of the entire central meeting portion of the two flexed portions of the diaphragm.

45 8. A diaphragm for radio loud speakers or the like of celluloid flexed into two substantially quarter-circle formations having a central meeting portion, edge portions and end portions, a positive stiffening area in rear of the line of juncture at the central
50 meeting portion of the flexed portions, said stiffening area being of a capacity sufficient to prevent whipping of the end portions and insure bodily movement of the entire central meeting portion of the two flexed portions of the diaphragm.

55

9. A diaphragm for radio loud speakers or the like of celluloid flexed into two substantially quarter-circle formations having a central meeting portion, edge portions and end portions, the line of juncture at the central meeting portion being curved rearwardly from the ends to the center to gradually reduce the mass and inertia toward the end portions.

10. A diaphragm for radio loud speakers

or the like of celluloid flexed into two substantially partially circular formations having a central meeting portion, edge portions, and end portions, the line of juncture at the central meeting portion being curved rearwardly from the ends to the center to gradually reduce the mass and inertia toward the end portions.

11. A diaphragm for radio loud speakers or the like of suitable material flexed into two substantially quarter-circle formations having a central meeting portion, edge portions and end portions, the line of juncture at the central meeting portion being curved rearwardly from the ends to the center to gradually reduce the mass and inertia toward the end portions.

12. A diaphragm for radio loud speakers or the like of suitable material flexed into two substantially partially circular formations having a central meeting portion, edge portions and end portions, the line of junction at the central meeting portion being curved rearwardly from the ends to the center to gradually reduce the mass and inertia toward the end portions. 85

13. A diaphragm for radio loud speakers or the like of suitable material flexed into two substantially quarter-circle formations having a central meeting portion, edge portions and end portions, the line of juncture at the central meeting portion progressing rearwardly from the ends to the center of the diaphragm to gradually reduce the mass and inertia toward the end portions.

14. A diaphragm for radio loud speakers or the like of celluloid flexed into two substantially quarter-circle formations having a central meeting portion, edge portions and end portions, the line of juncture at the central meeting portion progressing rearwardly from the ends to the center of the diaphragm to gradually reduce the mass and inertia toward the end portions.

15. A diaphragm for radio loud speakers or the like formed of a sheet of celluloid partially split to provide two diaphragm portions adapted to be flexed into substantially partially circular formations, the unsplit portion of the sheet lying in rear of the two diaphragm portions to form a stiffening area. 1115

16. A diaphragm for radio loud speakers or the like formed of a sheet of suitable material partially split to provide two diaphragm portions adapted to be flexed into substantially partially circular formations, the unsplit portion of the sheet lying in rear of the two diaphragm portions to form a stiffening area. 120

17. A diaphragm for radio loud speakers 125
or the like formed of a sheet of suitable material partially split to form two diaphragm portions, the unsplit portion of the sheet forming a central meeting portion for the two diaphragm portions. 130

18. A diaphragm for radio loud speakers or the like formed of a sheet of celluloid partially split to form two diaphragm portions, the unsplit portion of the sheet forming a central meeting portion for the two diaphragm portions. 70
19. A diaphragm for radio loud speakers or the like including two diaphragm portions of celluloid, a strip of celluloid disposed between the two diaphragm portions to space them apart, the surfaces of the said strip and the surfaces of the two diaphragm portions in contact therewith being united to form a unitary structure. 75
20. A diaphragm for radio loud speakers or the like including two diaphragm portions flexed into two substantially partially circular formations, a strip of stiff material interposed between the two diaphragm portions at the central meeting portions thereof to space the same apart, said strip of stiff material extending in rear of and beyond the line of juncture of two diaphragm portions to form a positive stiffening area for the dia- 80 phragm. 90
21. A diaphragm for radio loud speakers or the like, of suitable material flexed into two substantially partially circular formations having a central meeting portion, edge 95 portions and end portions, the substantially partially circular formations being spaced apart at the line of their juncture, a positive stiffening area in rear of the line of juncture of the flexed formations, said stiffening area being of a capacity sufficient to prevent whipping of the end portions and insure bodily movement of the entire central meeting portion of the two flexed formations of the diaphragm. 100
22. A diaphragm for radio loud speakers or the like of suitable material flexed into two substantially quarter-circle formations having a central meeting portion, edge portions and end portions, the substantially quarter- 105 circle formations being spaced apart at the line of their juncture, a positive stiffening area in rear of the line of juncture of the flexed formations, said stiffening area being of a capacity sufficient to prevent whipping of the end portions and insure bodily movement of the entire central meeting portion of the two flexed formations of the dia- 110 phragm. 115
23. A diaphragm for radio loud speakers or the like of celluloid flexed into two substantially partially circular formations having a central meeting portion, edge portions and end portions, the substantially partially circular formations being spaced apart at the 120 line of their juncture, a positive stiffening area in rear of the line of juncture at the central meeting portion of the flexed formations, said stiffening area being of a capacity sufficient to prevent whipping of the end portions and insure bodily movement of the entire central meeting portion of the dia- 125 phragm. 130
24. A diaphragm for radio loud speakers or the like of celluloid flexed into two substantially quarter-circle formations having a central meeting portion, edge portions and end portions, the substantially quarter-circle formations being spaced apart at the line of their juncture, a positive stiffening area in rear of the line of juncture at the central meeting portion of the flexed formations, said stiffening area being of a capacity sufficient to prevent whipping of the end portions and insure bodily movement of the entire central meeting portion of the diaphragm. 70
25. A diaphragm for radio loud speakers or the like of suitable material flexed into two substantially partially circular formations having a central meeting portion, edge portions and end portions, a layer of stiff material interposed between the substantially partially circular formations to space the same apart at their line of juncture, the dia- 85 phragm material and the interposed stiffening layer extending in rear of the line of juncture of the flexed formations to form a positive stiffening area of sufficient capacity to prevent whipping of the end portions and insure bodily movement of the entire central meeting portion of the flexed formations of the diaphragm. 90
26. A diaphragm for radio loud speakers or the like of suitable material flexed into two substantially quarter-circle formations having a central meeting portion, edge portions and end portions, a layer of stiff material interposed between the flexed formations to space the same apart at their line of juncture, the diaphragm material and the inter- 95 posed stiffening material extending in rear of the line of juncture of the flexed formations to form a positive stiffening area of sufficient capacity to prevent whipping of the end portions and insure bodily movement of the entire central meeting portion of the dia- 100 phragm. 105
27. A diaphragm for radio loud speakers or the like of celluloid flexed into two substantially partially circular formations having a central meeting portion, edge portions and end portions, a positive stiffening area including continuations of the diaphragm and a piece of stiff material interposed be- 110 tween the diaphragm continuations and spacing the flexed formations apart, at their line of juncture, the stiffening area being of a capacity sufficient to prevent whipping of the end portions and insure bodily movement of the entire central meeting portion of the dia- 115 phragm. 120
28. A diaphragm for radio loud speakers and the like of celluloid flexed into two substantially quarter-circle formations having a central meeting portion, edge portions and end portions, a positive stiffening area in 125 130

rear of the line of juncture of the flexed formations, the stiffening area including a piece of stiff material interposed between continuations of the diaphragm material and spacing the flexed formations apart at their line of juncture, the stiffening area being of a capacity sufficient to prevent whipping of the end portions and insure bodily movement of the entire central meeting portion of the diaphragm.

In testimony whereof I affix my signature.
CHARLES HUGH DUFFY.
